UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

PERFORATING-MACHINE.

1,120,881.

Specification of Letters Patent. Patented Dec. 15, 1914.

Application filed April 22, 1911. Serial No. 622,688.

To all whom it may concern:

Be it known that I, ALEXANDER M. ALEXANDER, a citizen of the United States, residing at Beverly, in the county of Essex and State of Massachusetts, have invented certain Improvements in Perforating-Machines, of which the following description, in connection with the accompanying drawings, is a specification, like reference characters on the drawings indicating like parts in the several figures.

This invention relates to punching machines for producing ornamental perforations in stock such, for example, as quarters and other parts of boots and shoes, and is concerned more particularly with certain improvements upon machines of the type of that shown and described in the patent to Flynt, No. 941,704.

20 In the machine shown in the patent means are provided for insuring that the spaces between perforations extending in a curved line are uniform with those between perforations extending in a straight line, and this result is brought about by providing a punch feed of a certain type. It often happens, however, that the stock to be ornamented in a given factory consists in whole or in a considerable part of pieces having 25 comparatively straight edges. Under such circumstances, owing to the fact that a punch feed is ordinarily a comparatively slow feed, it is desirable that means be provided for changing from the punch feed to 30 a faster moving feed.

Accordingly one feature of the present invention consists in the provision in a machine of the class described of means for causing the punch to feed the stock, means 40 for feeding the stock independently of the punch and means under control of the operator for rendering a selected one of the feeding means operative. And preferably the punch-feed mechanism is actuated directly 45 from the main driving shaft, the independent feed mechanism from a counter-shaft, and means are provided under the control of the operator for connecting the main shaft with the counter-shaft.

50 When the punch feed is being used a stripper is employed which engages the stock in the line of the perforations while the punch is being withdrawn from the stock and is intermittently raised and with- 55 drawn from the path of lateral movement of

the punch to permit the punch to swing past it; and for the production of uniformly spaced perforations, particularly if the edge of the work is curved, it is desirable that the stripper engage the stock at a point midway between the extreme lateral positions which the punch occupies during the feeding operations.

To this end another feature of the invention consists in the provision with a machine of the class described having a punch movable longitudinally to perforate the stock and laterally to feed it, and a stripper actuated to engage the stock intermittently, of means for adjusting the stripper longitudinally of the line of perforations.

With this construction and arrangement of parts it is possible to cause the stripper to engage the stock at a point exactly midway between the extreme positions occupied by the punch during the feeding movement irrespective of the extent of such movement. And it is also possible, in case it is desirable, to cause the stripper to engage the stock at a point distant a given distance from the 80 middle point referred to above.

In producing a line of perforations in the margin of a piece of stock having a curved edge it is possible, if the operator is sufficiently skilled, to place the line parallel to 85 the edge of the stock. In order, however, to facilitate such placing and to insure its accuracy another feature of this invention consists in the provision in a perforating machine of a punch, means for forcing the 90 punch into the stock, and feed mechanism including automatic means for causing the line of perforations to follow the curve of the edge of the stock. In the illustrated embodiment of the invention an edge guide is 95 fast to and movable with the punch carrier during the lateral movement of the punch while the stock is engaged by the stripper so that the edge guide as it moves rearwardly in a straight path will bear against 100 the curved edge of the stock and force the stock to turn about the point engaged by the stripper.

These and other features of the invention including certain details of construction and combinations of parts will be set forth in connection with the accompanying drawings and will be pointed out in the appended claims.

Referring now to the accompanying draw- 110

ings, Figure 1 is a side elevation of the machine in which the present invention is embodied; Fig. 2 is a front elevation; Fig. 3 is a perspective of the forward portion of the 5 machine; Fig. 4 is a cross section of the upper portion of the punch bar and punch bar carrier; Fig. 5 is a perspective showing the stripper and its actuating mechanism; Fig. 6 is a perspective showing the independent means for feeding the stock; and Fig. 7 is a perspective showing the guide for 10 use with work having curved edges.

Rotatably mounted in brackets in the frame 1 is a driving shaft 3 upon which is 15 mounted a driving pulley 5 adapted to be continuously rotated from any suitable source of power; and this pulley is arranged to rotate the shaft through a suitable clutch which may be thrown into actuation by de- 20 pressing a link 7 normally held in the position shown in Fig. 1 by the spring 9. The details of the clutch mechanism form no part of the present invention and will not be further described. The shaft 3 has fast 25 upon it four cams 11, 13, 111 and 15, and an eccentric 17. As will be presently described the cam 13 serves to reciprocate the punch; the cams 11 and 111 move the punch laterally to feed the stock; the cam 15 operates 30 the stripper, and the eccentric 17 operates the counter-shaft which in turn drives the independent feed mechanism.

The punch bar carrier 19 is fast to a slide 21 which is movable horizontally in a dove- 35 tailed guideway as best shown in Figs. 2 and 3, a spring 23 being provided which normally holds the punch bar carrier in the extreme right hand position as viewed in Fig. 2. In order to move the punch bar 40 carrier in opposition to the spring, a lever 25 is pivoted to said carrier at 27 and carries at its upper ends two cam rolls 29 and 291 which coöperate with the cams 11 and 111, said cams being of identical outline. In 45 order to hold the lever 25 in operative position as well as to vary the effective throw of said lever, when desired, a fulcrum-roller 31 (see Fig. 3) is carried by a bracket 33 the stem of which is slidably mounted in a 50 slot 35 cut through a hinged plate 37, said plate being mounted to swing about an axis passing through the center of the screw 39. A thumb screw 41 (see Figs. 1 and 2) is arranged to clamp the bracket 33 in adjust- 55 ed position, and a hooked bolt 43 extending through the hinged member or door 37 is provided for locking the door in closed position, the hook engaging a cylindrical stud on the frame (not shown) and the outer end 60 of the bolt being threaded to receive a thumb- 65 nut 45. With this construction it is possible by varying the position of the roller 31, which serves as a fulcrum, to vary the effective throw of the lever 25 and thus the ex- 70 tent of lateral movement imparted to the

punch. It should be noted that by dropping the bracket 33 to its lowermost position the fulcrum 31 will cease to be operative, and no lateral movement whatever will be im- 75 parted to the punch. By making the part 37 in the form of a swinging plate or door instead of an integral part of the frame easy access to the punch carrier and its associated mechanism is made possible, it being evi- 80 dent that when the door has been swung open, as shown in Fig. 3, the punch bar carrier, together with the associated parts, may be moved to the right as viewed in Fig. 2 until it is free from the dove-tailed guide- 85 way, and may then be removed entirely from the machine.

The punch bar carrier is provided with a cylindrical bore in which is slidably mounted the punch bar. Referring more particu- 90 larly to Fig. 4, this bar comprises two sec- 95 tions 47 and 49. The section 47 is normally held in raised position by a spring 48, the lower end of which rests upon a shoulder in the lower portion of the bore in the punch bar carrier. The upper section 49 of the punch bar is provided with a hollow exten- 95 sion 56 which fits loosely upon the upper end of the section 47, and in this extension is an abutment block 51 mounted upon an eccen- 100 tric 53, which is fast to a stud 55, said stud being supported in bearings in the exten- 105 sion 56.

On the end of the stud 55 is fastened an adjusting lever 57 (see Figs. 2 and 3) which 100 may be held in adjusted position by means of a clamp 59 (see Fig. 1) provided with a locking nut 61, said clamp coöperating with a plate 63 carried by a bracket on the hollow extension 56. The purpose of this construction is to vary the lowermost position which 105 the punch occupies during the operation of the machine. By turning the lever 57 and thereby the eccentric 53, the abutment block 51 may be raised or lowered with respect to the upper section 49 of the punch bar. It 110 will thus be apparent that the effective length of the punch bar may be increased or diminished as desired.

In order to hold the stock down upon the bed 65 while the punch 67 is being withdrawn a stripper 69 is provided. This stripper (see Fig. 5) is carried by a stem 71 slidably mounted in a socket or holder 73 and normally held in the position shown by a spring 75 which encircles a reduced portion of the stem 71 and abuts with one end a shoulder on said stem and with the other end the base of a hollow nut threaded into the socket and provided with a knurled head 77. The socket 73 is provided at its 115 lower portion with an eye through which passes a rock-shaft 85, said rock-shaft being provided with a groove (not shown) to receive the end of the screw 76, so that longitudinal movement of the rock-shaft 85 120 125 130

causes like movement of the socket 73 and with it of the stripper. Projecting through a slot in the socket 73 is a pin 79 which is fast to the stem 71, and the socket is also provided with a transverse slot 80 so that if the nut 81 is pulled upwardly and given a quarter turn the stripper 69 may be held in inoperative position. It will be understood that the stripper should be held in contact with the work during the time that the punch is being withdrawn from the stock and that it should be out of contact with the work during the time that the punch is feeding the stock forward. In order to accomplish this movement a toe 83 is caused to coöperate with the pin 79. This toe is fastened to the rock-shaft 85 by a pin 87 so that, when the shaft is rocked, the pin 79 and with it the stripper 69 is intermittently lifted against the force of the spring 75. In order to permit the shaft to be rocked and at the same time to permit said shaft to be moved longitudinally, the end of the said shaft is split as shown at 89 to receive a pin (not shown) which passes through said slot and through a crank 91. This crank is integral with a sleeve 92 (see Fig. 2) which is held in fixed longitudinal position by means of a finger 94 and through which the rock-shaft is slidable. The crank 91 is connected by a link 93 with a bell-crank lever 95 pivoted at 97 to the frame of the machine, and this bell-crank lever carries at its upper end a roll 99 which coöperates with the cam 15 on the main driving shaft 3. As the cam is rotated the shaft 85 is rocked, and the stripper 69 is intermittently raised from the stock by the toe 83 and forced down upon it by the spring 75.

In order to raise the stripper when desired as, for example, when a piece of work is to be introduced into the machine, a second bell-crank lever 101, pivoted to the frame at 103 and normally held in inoperative position by a spring 105, is attached to a chain 107 which passes over a pulley 109 and is connected with a suitable treadle (not shown). It is sometimes desirable to adjust the stripper with respect to the punch in the direction of the lateral movement of the punch, and in order to provide for such adjustment the socket 73 is provided with a second eye 113 through the bore of which is threaded an adjusting screw 115 which is rotatably mounted in the frame of the machine but is held from longitudinal movement with respect thereto. By turning the screw 115 in one direction or the other it is possible to adjust the stripper in the direction of the lateral movement of the punch and thereby to locate the stripper at the exact center of the path described by the punch in said lateral movement or at any other desired point.

In order to guide the edge of the work, an edge gage 117 is provided. This gage may be of any approved form; and of the one shown it will be sufficient to say that an upright stud 119 integral with it is angularly movable in a socket 121 which in turn may be clamped to a bracket 123 by turning a thumb nut 125, the turning of said nut serving also to tighten the bracket 123 upon the rod 127 upon which it is slidable. It will thus be seen that by loosening a single screw the gage 117 may be adjusted forward and back upon the rod 127 as well as angularly about the axis of the stud 119.

It often happens that the edge of the work to be perforated is curved; and, in order to cause the line of perforations to be located automatically at a uniform distance from the edge, a guide for curved work (best shown in Fig. 7) is provided, it being understood that this guide is to be substituted for the gage 117 when the character of the work is suitable. This guide is arranged to be reciprocated, and in the illustrative machine is shown as fast to the punch bar carrier; but it should be understood that said guide may be mounted upon any suitable part. Referring to this figure, the guide 129 is provided with a horizontal arm 131 which is held in a bracket 133 by means of a set-screw 135, and this bracket is provided with slides 137 which are received in guideways 139 formed in a collar 141, said collar being clamped about the punch bar carrier 19 by means of a binding screw 143.

Fixedly held by the punch bar carrier 19 is a screw threaded rod 145 adapted to receive a thumb nut 147 the shank of which is held by an upstanding yoke 149 of the bracket 133. Manipulation of the thumb nut 147 thus serves to adjust the guide 129 toward and from the punch in the direction of the lateral movement of the punch. The operative portion of the guide itself comprises a supporting member 151 arranged to underlie the stock and a presser foot 153 pivoted to the guide at 155, said presser foot being normally held downwardly by a spring 157, the extent of the downward movement being limited by a set-screw 159.

The operation of this device is as follows: After the punch has been raised from the stock and occupies the position shown in Fig. 7 the next movement of the punch is to the right as viewed in that figure. During this movement the stripper 69 remains in engagement with the stock, and the guide 129 swings backwardly or to the right with the punch. In case the edge of the work is straight, it is evident that the angular position of the work will not be affected, but if the work is curved the guide

on its backward movement engages the curved edge of the work and swings the work about the point engaged by the stripper 69. The position of the punch and of the guide at the end of their backward movement are shown in dotted lines in Fig. 7. In this figure the original position of the work is shown in full lines and the position to which the work is turned by 10 the operation of the machine described above is shown in dash lines; and it will be noted that the extent to which the stock is turned is directly dependent upon the radius of the curvature of the edge of the 15 work.

As has been stated, one of the principal objects of the present invention is to provide a machine in which the stock may be fed by the punch or by an independent feed 20 mechanism according to the nature of the work which is to be operated upon. Any suitable sort of independent feed mechanism may be employed.

Referring now more particularly to Fig. 25 6, a feed plate 161 having one end held in engagement with a cam 163 by a spring 165 is provided at its opposite end with a perforation through which passes an actuating rod 167 which is adapted to swing about 30 a pivot screw 169. The actuating rod 167 is formed with a lug 175 which acts as a fulcrum the position of which, as will presently appear, determines the extent of throw 35 of the feed plate 161. In order to adjust the position of this fulcrum, the pivot 169 is carried by a bracket on a slide bar 177 which slides through the arms of a yoke 179; and this slide bar may be moved longitudinally by means of an adjusting screw 40 181 provided with a knurled head 183 and a lock nut 185. The actuating rod 167 is moved angularly in one direction by a spring 187 which has one end fastened to an upright post 189. To move the actuating rod in the other direction a link 191 45 has at one end a pin-and-slot connection with the upright post 189 and at the other end is pivoted at 193 to a second link 195. This latter link carries at its end a roll 50 197 which is held against a cam 199 on the counter-shaft 201 by means of a spring 203. The shaft 201 extends into a socket in the shaft 205, and the two shafts are connected by means of a clutch collar 207 55 keyed to the shaft 201 and provided with a projecting lug 209 which is received in a socket formed on the shaft 205. A lever 211 pivoted at 213 to a fixed support carries at its inner end a shifting yoke 215 60 of the ordinary type by which the clutch collar may be thrown into and out of operative position. A stop collar 216 is provided on the shaft 201 to limit the movement of the clutch collar 207. The shaft 65 205 is constantly rotated from the eccentric

17 on the main driving shaft by an eccentric rod 218 provided at its lower end with a pin which coöperates with a slotted crank 217 fast to the end of the shaft 205. It will be clear that when the shaft 201 is 70 rotated the cam 199 through the roller 197 and links 195, 191 will impart movement to the actuating rod 167 in one direction while the spring 187 will move said rod in the reverse direction. The purpose of the 75 cam 163 and the spring 165 is to raise and lower the feed plate 161 at the proper points in its path.

In order to hold the work down upon the toothed portion of the feed plate 161 when the feed mechanism described above is being used a presser foot in the form of a conical presser roll 219 is rotatably mounted on an inclined stud 221 which is held by a set-screw 223 in a block 225. This block is fast 80 to a stem 227 which is slidably mounted on an upright bearing 229 and is urged downwardly by a spring, not shown, which contacts at one end with the shoulder on the stem and at the other with the base of a 85 counter-bore in the bearing. The stem is provided with a pin 231 (see Fig. 2) and the bearing with a slot 233 to form a bayonet joint so that when the presser roll is not in use it may be held out of the way in 90 raised position as shown in all the figures in which it appears. The bearing 229 is clamped in a yoke on a collar 235 by means of a screw 237, said collar in turn being held in place by means of a set-screw 239. 95

As illustrated in Figs. 1, 2 and 3, the punch feed mechanism is arranged to be operative; and as the shaft 3 is rotated the cam 13 and the spring 48 serve to reciprocate the punch bar while the cams 11, 111 and the spring 23 serve to move it laterally. 105 If now it is desired to change from the punch feed to the independent feed, the fulcrum roller 31 is lowered until it is out of operative position; the knurled head 81 is pulled upwardly and given a quarter-turn thereby raising the stripper 69; the presser roll 219 is given a quarter-turn whereupon the catch-pin 231 is free to move down in the slot 233, and the roll 219 is pressed upon 110 the work table; and the lever 211 is moved to connect the counter-shaft 201 with the main driving shaft. 115

Having thus described my invention, what I claim as new and desire to secure by Letters Patent of the United States is:—

1. A machine of the class described having, in combination, means for causing the punch to feed the stock, means for feeding the stock independently of the punch, and means under control of the operator for rendering either one of the feeding means operative or inoperative independently of the other. 125

2. A machine of the class described hav- 130

- ing, in combination, a punch, means for forcing said punch into the stock, means for causing the punch to feed the stock, mechanism for feeding the stock independently 5 of the punch, means under control of the operator for rendering said independent feed mechanism operative and means for rendering the punch feeding means inoperative.
- 10 3. A machine of the class described having a punch, means for forcing said punch into the stock, means for moving the punch laterally to feed the stock, in combination with means for feeding the stock independently 15 of the punch, and means under control of the operator for rendering the laterally moving means inoperative.
4. A machine of the class described having, in combination, a punch, a driving 20 shaft, means coöperating with said shaft to move said punch longitudinally to punch the stock and laterally to feed the stock, a counter-shaft, independent feed mechanism adapted to be actuated thereby, means under control of the operator for connecting 25 said counter-shaft with said driving shaft and for disconnecting it therefrom.
5. A machine of the class described having, in combination, a punch, means for 30 forcing said punch into the stock, means for moving the punch laterally to feed the stock, a stripper for engaging the stock at a point approximately in the path of lateral movement of the punch, means for actuating said 35 stripper intermittently and means for adjusting said stripper in a direction parallel to that of the lateral movement of said punch.
6. A machine of the class described having, in combination, a punch, means for 40 forcing said punch into the stock, means for moving the punch laterally to feed the stock, a stripper for engaging the stock, a spring tending to move said stripper into 45 engagement with the stock, a cam engaging said stripper intermittently to lift it, and means for locking said stripper in inoperative position.
7. A machine of the class described having, in combination, a punch, means for 50 forcing said punch into the stock, means for moving the punch laterally to feed the stock, a stripper for engaging the stock, a holder in which said stripper is mounted, 55 a spring tending to move said stripper with respect to said holder, a rock-shaft slidable in bearings in the frame of the machine, said shaft being angularly movable with respect to said holder but being held from 60 longitudinal movement with respect thereto, and means for adjusting said holder and shaft longitudinally of said shaft.
8. In a machine for perforating a piece of stock having a curved edge, means for 65 engaging said piece at a predetermined
- point, means for automatically turning said piece about said point, and means for varying the location of said point and thereby the extent to which said piece is turned.
9. A machine for producing a line of perforations in a piece of stock having, in combination, a punch, means for forcing said punch into the stock, and means for feeding the stock, said means including an edge 70 guide, means for moving said guide along the edge of the work and means for adjusting said guide in line with the edge of the stock.
10. A machine for producing a line of perforations in a piece of stock having, in combination, a punch, means for forcing said punch into the stock, and means for feeding the stock, said means including an edge 75 guide, means for moving said guide along the edge of the work and means for adjusting said guide in line with the edge of the stock.
11. A machine for producing a line of perforations in a piece of stock having, in combination, a punch, means for forcing said 80 punch into the stock, means for moving the punch laterally to feed the stock and means including an edge guide movable laterally with said punch for causing the line of perforations to follow the curve of the edge 85 of the stock.
12. A machine for producing a line of perforations in a piece of stock having, in combination, a punch, means for forcing said punch into the stock, means for moving the punch laterally to feed the stock, a stripper 90 for engaging the stock during the rearward movement of the punch, and an edge guide movable with the punch and adapted to engage a curved edge of the stock to swing 95 said stock about the point engaged by the stripper.
13. A machine of the class described having, in combination, a punch, means for reciprocating said punch longitudinally to 100 force it into the stock, means for moving said punch laterally to feed the stock, and a plate hinged to the frame of the machine and adapted to be swung outwardly to give 105 access to the punch.
14. A machine of the class described having, in combination, a punch bar, means for reciprocating said bar, a carrier in which said bar is mounted, means including a lever and a fulcrum for moving said carrier laterally, a plate by which said fulcrum is carried, said plate being pivoted to the frame 110 of the machine, and means for locking said plate in closed position.
15. A machine of the class described having, in combination, a punch, a bar by which said punch is carried, said bar comprising an upper and a lower section, a spring for sustaining the lower section, the upper section being in the form of a cap, a block 115 120
- 130

slidably mounted in said cap, means for adjusting said block with respect to said cap, and means for depressing said cap and thereby said punch.

5 16. A machine of the class described having a punch and means for causing said punch to travel in a rectangular path in combination with a stripper for engaging the stock at a point approximately in the 10 path of the punch and means for moving said stripper intermittently out of the path of the punch.

17. A machine of the class described having a punch bar, a punch carried thereby 15 and means for reciprocating said punch bar in combination with a punch bar carrier having a slide, a guide for sustaining said slide, a spring for moving said carrier laterally in one direction and positive means

for moving said carrier in the opposite direction.

18. A machine of the class described having a punch bar, a punch carried thereby, and means for reciprocating said punch bar in combination with a punch bar carrier 25 having a slide, a guide for sustaining said slide, a spring for moving said carrier laterally in one direction and positive means including an adjustable fulcrum for moving said carrier in the opposite direction. 30

In testimony whereof I have signed my name to this specification in the presence of two subscribing witnesses.

ALEXANDER M. ALEXANDER.
